UNITED STATES PATENT OFFICE.

CHACE D. GILMORE, OF HIGHLAND PARK, MICHIGAN.

DESIGN FOR A COMBINATION SALT AND PEPPER CELLAR.

50,344.

Specification for Design.

Patented Feb. 20, 1917.

Application filed December 6, 1916. Serial No. 135,500. Term of patent 14 years.

To all whom it may concern:

Be it known that I, CHACE D. GILMORE, a citizen of the United States, residing at Highland Park, in the county of Wayne and State of Michigan, have invented a new, original, and ornamental Design for a Combination Salt and Pepper Cellar, of which the following is a specification, reference being had to the accompanying drawings, forming a part thereof, in which—

Copies of this patent may be obtained for five cents each, by addressing the "Commissioner of Patents, Washington, D. C."

Fig. 2 is a top plan view of the same; and Fig. 3 is a bottom plan view.

I claim:

The ornamental design for a combination salt and pepper cellar, substantially as shown.

In testimony that I claim the foregoing as my own, I have hereto affixed my signature in the presence of two witnesses.

CHACE D. GILMORE.
